CLAIM

The ornamental design for a unitary eyeglass lens, as shown and described.

DESCRIPTION

FIG. 1 is a front perspective view of the unitary eyeglass lens of the present invention;

FIG. 2 is a rear elevational view thereof;

FIG. 3 is a top plan view thereof;

FIG. 4 is a front elevational view thereof;

FIG. 5 is a left-side elevational view thereof, the right-side elevational view being a mirror image thereof; and,

FIG. 6 is a bottom plan view thereof.
